K. ENGEL.

METHOD OF MAKING SHOES.
APPLICATION FILED JULY 19, 1918.

Patented May 10, 1921.

UNITED STATES PATENT OFFICE.

KARL ENGEL, OF ARLINGTON, MASSACHUSETTS, ASSIGNEE TO UNITED SHOE MACHINERY CORPORATION, OF PATERSON, NEW JERSEY, A CORPORATION OF NEW JERSEY.

METHOD OF MAKING SHOES.

1,377,329.

Specification of Letters Patent. Patented May 10, 1921.

Application filed July 19, 1918. Serial No. 245,658.

To all whom it may concern:

Be it known that I, KARL ENGEL, a citizen of the United States, residing at Arlington, in the county of Middlesex and State 5 of Massachusetts, have invented certain Improvements in Methods of Making Shoes, of which the following description, in connection with the accompanying drawings, is a specification, like reference characters 10 on the drawings indicating like parts in the several figures.

This invention relates to methods of making shoes and is herein disclosed with particular reference to the manufacture of shoes 15 having outwardly directed flanges about the heel portions, for example, stitchdown shoes. It is to be understood, however, that in its broader aspects, the invention is applicable to the manufacture of shoes of the 20 stitchdown or other types in which the flanges at the rear ends are inwardly directed.

By a common method of making stitchdown shoes, an upper is prepared with an 25 outwardly directed flange and the flange is secured to the margin of a sole or innersole before the insertion of a last. A last is then inserted to stretch and shape the upper and the shoe is completed generally by the attachment of an outsole to the 30 outwardly extending portion of the upper and innersole by usual means. If the upper is lined, it is customary to sew the upper and lining together to form a counter pocket in which a counter or heel stiffener is placed 35 before the upper is attached to the innersole. After the counter is inserted in the counter pocket, the upper is passed to the operator of the heel molding machine to have the usual flange formed upon the rear 40 portion of the upper and counter. Heretofore, between the counter inserting and molding operations, the counter has been likely to become misplaced in the pocket or 45 to drop out, requiring additional time of the molding machine operator to relocate or replace the stiffener in the pocket before the molding operation. In case this readjustment of the counter was neglected at this stage in the operations, it was impossible 50 to correct it later and the style, comfort, and wearing qualities of the shoe were impaired.

An object of this invention is to provide an improved method of making shoes which 55 will not only prevent displacement of the

counter at any stage subsequent to its insertion but also will enable the heel molding operation to be dispensed with entirely under favorable conditions. Certain advantages of this method are obtained also 60 when it is applied to the treatment of uppers which have no lining and to which the counter or stiffener is sewed along its curved edge.

In accordance with my improved method, 65 the tempered counter and upper are secured together by a line of fastenings located along the margin of the upper. The upper and counter are thus permanently located relatively to each other and all danger of 70 displacement of the counter is avoided. The line of fastenings is preferably located at a distance from the edge of the upper corresponding to the width of the sole attaching flange and substantially along the line 75 where the upper and stiffener will be bent in the formation thereon of the sole attaching flange. When upper penetrating fastenings are used, the penetration of the upper and stiffener by the fastenings, particularly when they are close together, so weakens the upper along the flange turning line as materially to facilitate the molding or flange turning operation as such when performed and, under favorable conditions, 80 as when the material of the counter stiffener is well tempered, the counter and upper may be secured to the sole along the line of fastenings by a sewing operation without the previous flange forming operation. In 85 this case the insertion of the last in the shoe after the margin of the upper has been attached to the sole is depended upon to form the portion of the shoe including the stiffener to the shape of the last and to this end the upper is preferably allowed to dry and 90 set in the shape given to it by the last before the last is removed. Upon the insertion of the last, the counter will bend readily along the line where it has been secured to the upper and consequently weakened by the line of perforations made by the line of securing means, for example, stitches or staples. The flange bending line is thus 95 predetermined by the line of perforations or penetrations.

In the drawings,—

Figure 1 is a side view, partly in section, of a shoe having a counter pocket with a heel stiffener or counter inserted therein;

Fig. 2 is a side view similar to Fig. 1

100

110

showing the shoe after the counter has been secured in the pocket by a line of fastenings near its lower margin;

Fig. 3 is a fragmentary perspective view, 5 partly in section, of the rear portion of the shoe in the condition shown in Fig. 2;

Fig. 4 is a view similar to Fig. 3 showing the margin of the upper and counter turned outwardly along the line where they are 10 secured together;

Fig. 5 is a view similar to Fig. 4 showing the outturned flange of the counter and upper attached to the sole;

Fig. 6 is a side view, partly in section, of 15 the shoe after the last is inserted; and

Fig. 7 is a view, partly in section, of a shoe made in accordance with this method in which the margin of the counter and upper materials is turned inwardly.

20 In the practice of my method, an upper A having a lining B is prepared and a counter pocket formed by sewing the upper and lining together along the line C. A counter or heel stiffener D, after being properly tempered, is inserted into the pocket as indicated in Fig. 1. During subsequent operations upon the upper and stiffener while in this condition, the stiffener is very likely to become misplaced in the counter pocket or 25 to fall out of the pocket altogether and time of the operator is consumed in replacing the stiffener or in examining the parts to ascertain whether or not they are properly located. It is also difficult to bend either inwardly or outwardly the margin of the stiffener and upper to form the sole attaching flange along a well defined line. Accordingly, in accordance with my method, the stiffener is secured in place in the counter 30 pocket by a number of fastenings at E (Figs. 2 and 3) located along the line where the materials are to be bent and providing beyond the line of fastenings a width of material sufficient to form the sole attaching flange. In order to facilitate the bending of the stiffener and upper, it is preferable to provide a continuous line of upper 35 penetrating fastenings, the penetrations or perforations of the upper being sufficiently close together to weaken the material along the flange turning line. In Figs. 2 and 3, a line of stitches is shown at E by which the desired results are obtained. The flange, that is, the margin beyond the stitches E, is 40 next turned into the position shown in Fig. 4. By reason of the weakening of the material along this flange turning line by the perforation of the stock by the needle and the fact that the counter is in temper, this 45 turning may be readily done or at least initiated by hand, though, of course, an upper forming machine may be used if desired to form the flange. It is, however, necessary only to give the flange a slight outward inclination since the next operation is effective

50 to complete the bending of the flange outwardly. This next operation consists in sewing or otherwise securing the flange to a sole or innersole. In this operation, if a sewing machine is employed, the pressure of the presser foot and the drawing up of the stitches will be effective to cause the flange to be bent at substantially right angles to the sides of the heel portion and to be drawn 55 into contact with the surface of the sole, as clearly shown in Fig. 5. It is to be understood that the remainder of the margin of the upper about the periphery of the shoe is also secured to the sole, for example, by turning it outward and sewing it to the sole 60 preferably as a part of the operation of securing the outturned flange of the counter and upper to the sole.

The shoe is now ready for the insertion of a last which is next inserted, the shoe being 65 then in the condition shown in Fig. 6. The insertion of the last shapes the upper including the heel portion and assists in giving the rear portion a well defined angle at the line of fastenings or stitches E. Preferably the last is allowed to remain in the shoe until the tempered counter has had time to dry out and set to the conformation 70 of the last.

While for some purposes the shoe is now 75 completed, it is desirable in some classes of work to secure another sole to the shoe by sewing it to the outturned flange and the projecting margin of the innersole and preferably also to apply at the same time a welt 80 to the top face of the flange. This, however, is a common operation in shoe making and does not need to be illustrated herein.

In Fig. 7 a shoe is shown in which the margin of the upper and counter is turned 85 inwardly; otherwise the method of making this shoe is the same as has already been described. The weakening of the materials by the line of perforations at E greatly facilitates the operation of turning the flange 90 whether the flange is turned outwardly or inwardly as shown in Fig. 7.

Having thus described my invention, what I claim as new and desire to secure by Letters Patent of the United States is:

1. That improvement in methods of making shoes which consists in forming a shoe upper with a counter pocket, inserting a tempered counter in the pocket, securing the counter to the upper along a line spaced 100 from its edge by the width of the sole attaching margin, forming the margin as a flange for attachment of a sole, and then completing the shoe in the usual manner.

2. That improvement in methods of making shoes which consists in forming a shoe upper with a counter pocket, inserting a counter in the pocket, securing the counter in the pocket by a line of fastenings located along the line where the upper and counter 110

are to be bent to form the sole attaching flange, securing said flange while the upper is off the last to a sole, inserting a last to shape the heel end of the upper, and then 5 finishing the shoe in the usual manner.

3. That improvement in methods of making shoes which consists in preparing an upper with a counter pocket, inserting a counter in the pocket, sewing the upper and 10 counter along the line where the upper and counter are to be bent, bending the margin of the upper and counter to form a flange the angle of which is located at the sewing line, and finishing the shoe in the usual 15 manner.

4. That improvement in methods of making shoes which consists in preparing an upper with a counter pocket, inserting an unmolded counter in the pocket, sewing the upper and counter along the line where the upper and counter are to be bent, attaching a sole to the shoe, inserting a last to shape the heel end of the upper and cause a sharp angle to be formed at the line of union of 20 the upper and counter between the upwardly extending counter portion and the flange, and then finishing the shoe in the usual manner.

5. That improvement in methods of making shoes which consists in preparing an upper with a counter pocket, inserting a tempered unmolded counter in the pocket, sewing the upper and counter together along the line where the upper and counter are to 30 be bent, molding the upper and counter with an outturned flange the angle of which is located at the sewing line, and finishing the shoe in the usual manner.

6. That improvement in methods of making stitch down shoes which consists in preparing an upper with a counter pocket, inserting a tempered unmolded counter in the pocket, sewing the upper and counter along the line where the upper and counter are to 40 be bent outwardly, attaching a sole to the margin of the upper adjacent to the line of stitching of the counter to the upper, inserting a last to shape the heel end of the upper and cause a sharp angle to be formed 45 at the line of union of the upper and counter between the upwardly extending counter portion and the outwardly directed flange, and then finishing the shoe in the usual manner.

55 7. That improvement in methods of making shoes which consists in preparing an upper with a counter pocket, inserting a tempered unmolded counter in the pocket, attaching the upper and counter together by 60 work penetrating fastenings along the line where the upper and counter are to be bent, molding the upper and counter with an outturned flange the angle of which is located at the securing line, and finishing the shoe in 65 the usual manner.

8. That improvement in methods of making shoes which consists in preparing a shoe upper, inserting a softened counter in proper relation to the upper, forming a line of perforations in the upper and counter along the 70 line where the sole attaching flange is to be formed at right angles to the face of the upper, sewing the flange portion to a sole while the upper is off the last, and then inserting a last to shape the heel portion of 75 the upper and form a well defined angle at the line of perforations.

9. That improvement in methods of making shoes which consists in preparing an upper, placing a counter in proper relation to 80 the upper, stitching the counter and upper together along a line located at the width of the flange to be formed thereon from the edge of the counter, sewing the upper and counter to a sole along a line between said 85 first line of stitches and the edge of the upper, inserting a last to bend the upper at the first line of stitches at a well defined angle to the flange, and then completing the shoe in 90 the usual manner.

10. That improvement in methods of making shoes which consists in preparing an upper and a tempered counter arranged in proper relation to each other, weakening the upper and counter along a line adjacent to 95 the margin of the upper and counter where the upper and counter are to be bent to form the sole attaching flange, bending said margin along the weakened line to form a flange for the attachment of a sole thereto, securing a sole to said flange nearer the edge of the margin of the upper and counter than the weakened bending line, inserting a last, and completing the shoe in the usual manner.

11. That improvement in methods of making shoes which consists in securing an unmolded counter to an upper by a line of fastenings extending along the margin of the upper and counter where the upper and counter are to be bent in lasting, the fastenings being sufficiently close together to weaken the upper materials along this line, then breaking over the margin of the upper to form a flange, securing the flange to the 100 sole, and completing the shoe in the usual manner.

12. That improvement in methods of making shoes which consists in securing an unmolded counter to an upper by a line of fastenings extending along the margin of the upper and counter where the upper and counter are to be bent in lasting, the fastenings being sufficiently close together to weaken the upper materials along this line, then breaking over the margin of the upper to form a flange, securing the flange to the sole while the upper is off the last, inserting a last, and completing the shoe in the usual manner.

13. That improvement in methods of making shoes which consists in preparing an upper, inserting a tempered unmolded counter in proper relation to the upper, attaching the upper and counter by work penetrating fastenings along the line where the upper and counter are to be bent, attaching a sole to the margin of the upper adjacent to the line of attachment of the counter to the upper, inserting a last to shape the heel end of the upper and cause a right angle to be formed at the line of attachment of the upper and counter between the sides of the counter portion and the portion at right angles to it and forming the sole attaching flange, and then finishing the shoe in the usual manner.

14. That improvement in methods of making shoes which consists in securing an unmolded counter to an upper by a line of stitches extending along the margin of the upper and counter where the upper and

counter are to be bent in lasting, the stitches being sufficiently close together to weaken the upper materials along this line, then breaking over the margin of the upper to form a flange, sewing the flange to the sole while the upper is off the last, inserting a last, and completing the shoe in the usual manner.

15. That improvement in methods of making shoes which consists in preparing a shoe upper, sewing a seam in the upper while it is yet unattached to the other parts of the shoe along its margin at a distance from its edge substantially equal to the width of the flange required for attachment of the sole, bending the upper at said seam, and completing the shoe by attachment of the sole to the flange in the usual manner.

In testimony whereof I have signed my name to this specification.

KARL ENGEL.
